CAR SUPPORTING MEANS

Edward J. Sattler, Mineral City, Ohio

Application February 27, 1935, Serial No. 8,494

10 Claims. (Cl. 105—4)

The invention relates generally to car supporting means, and more particularly to supporting means for carrying the load of two cars joined together at their ends, at the joint thereof.

Recent developments have provided high speed articulated trains for passenger service in which a single truck supports the adjoining ends of the cars, thereby substantially reducing the number of supporting trucks required. These trains are flexible laterally at their joints but not longitudinally, and the cars are not adapted to be uncoupled in use because there is no means of supporting the uncoupled end of each car.

Accordingly, when it is desired or becomes necessary to uncouple one or more of the cars of such trains, the uncoupling operation is slow and difficult requiring much time and labor, and is best performed in a repair shop because one end of each car must be jacked up or otherwise additionally supported when the car is uncoupled, and in such case, the temporary supporting means do not permit movement of the car.

Therefore, such articulated trains are not adapted nor intended for freight service where conditions require frequent coupling and uncoupling of the individual cars of a train, nor for passenger service whenever it is necessary to change the equipment in the train by adding or removing cars at or between terminals.

My invention provides means in a train of the articulated type for quickly and easily coupling and supporting the cars at any time or place, as is now the case with conventional type cars, such means being an integral part of the cars.

Moreover, the cars of a freight train must necessarily have draft means permitting some longitudinal movement of the cars relative to each other, in order that the available motive power is sufficient to start a relatively long train by imparting initial movement to the cars successively.

In high speed articulated trains wherein the individual cars have no movement longitudinally relative to each other, the length of the train is greatly limited because the available motive power must impart starting movement to the whole train as a unit, the desired result being to produce a solid or longitudinally unyielding train of cars resulting in a steady and smooth riding train.

In prior train and trailer car constructions it has been proposed to provide auxiliary supporting means for supporting the uncoupled end of a car, but the auxiliary supporting means do not cooperate with the main supporting means when the cars are in coupled position, but either are

rendered inoperative or arranged to idle on the car track or rails.

In constructions where the auxiliary support wheels are arranged to idle on the rails when the cars are coupled, the auxiliary wheels do not "track" properly due to unevenness of the rails because substantially none of the load is carried by the auxiliary wheels. In other words, the auxiliary wheels tend to leave the rails, which may cause serious damage or even disastrous results.

My construction provides means for distributing or equalizing the load to all main and auxiliary supports, which load must be substantially constant under all conditions of track irregularities.

It is therefore an object of the present invention to provide improved car supporting means at the joined ends of two connected cars, which means will permit uncoupling of the cars.

Another object is to provide auxiliary supporting means adjacent the main supporting means at the joint of two coupled cars, for cooperating with the main supporting means to support the load of the cars in coupled position.

A further object is to provide auxiliary supporting means for each car of a train of the articulated type, which means provides for uncoupling of the cars and for automatic coupling of the cars when they are moved together for connection.

Another object is to provide improved car support means at the joined ends of two connected cars, including means for permitting relative longitudinal movement of the cars in coupled position.

A still further object is to provide auxiliary supporting means for cars having a single main support at their joined ends, said auxiliary means being adapted to support one end of a car in uncoupled position and to cooperate with the main support for carrying part of the load of said car in coupled position.

And finally, it is an object of the present invention to embody all of the foregoing advantageous features in a relatively simple and inexpensive construction, which is adapted for use in passenger service, as well as in meeting the requirements of quick and easy coupling and uncoupling of individual cars in freight service, and which involves a minimum of manufacturing and maintenance cost.

The improvements comprising the present invention accomplish all of the foregoing and other objects in the means shown in the drawing and described in the following specification.

The present invention may be described in general terms as including, in combination with a main truck for supporting two connected cars at the joint thereof, an auxiliary support under the adjacent end of one of the cars, a load distributing member pivotally connected with said adjacent car end and connected at one end to said auxiliary support, the other end of said load distributing member being adapted to rest on the main support when the cars are in coupled position so that the load of said one car is distributed between the main support and the auxiliary support, the end of said load distributing member connected to the auxiliary support being adapted to form a rigid connection between the auxiliary support and the said car in uncoupled position, and a guide on the main support adapted to be movably engaged by the free end of said load distributing member when the cars are moved toward or away from each other, for transferring part of the load of said one car to or from the main support.

Referring to the drawing forming part hereof

Figure 1 is a fragmentary plan sectional view of the joined ends of two connected railway cars carried by my improved supporting means, the main supporting truck being shown in dot-dash lines;

Fig. 2 is a vertical sectional view taken substantially on line 2—2, Fig. 1;

Fig. 3 is a transverse sectional view substantially on line 3—3, Fig. 2, showing the auxiliary support in elevation; and

Fig. 4 is a transverse view taken on line 4—4, Fig. 1, showing a preferred form of coupling means.

Similar numerals refer to similar parts throughout the several views of the drawing.

While I have illustrated and described my invention as applied to railway cars, the invention is equally well adapted for use in any vehicle trailer construction where at least two cars or units are joined together and supported at or near the joint.

The improved car supporting means is shown in the drawing as supporting the joined ends of two railway cars indicated generally at 10 and 11. The under-frame work of each car preferably includes sill members 12 extending longitudinally of the car, a platform 13 being connected to the sill members at one end of the car, and a platform 14 being connected to the sill members at the other end of the car. Thus, the platform 13 of the car 10 is adjacent to the platform 14 of car 11.

The platform 13 is provided at its central portion laterally of car 10 with an enlarged portion 15 having an upwardly open depression or socket 16, U-shaped in cross section, formed therein, and the socket 16 preferably has the bottom wall 17, side walls 18 and end wall 19. A joint portion 20 depends from bottom wall 17 and has a swiveled connection with a joint portion 21 located at the center of the main supporting truck indicated generally at 22, which may be a four wheel truck of standard construction shown somewhat diagrammatically in the drawing and having the wheels 23 rolling on the track rails R.

Thus, the entire load of the end of car 10 adjacent to car 11 is carried by the main truck 22, and the joint portion 21 of the truck is located between the adjacent ends of cars 10 and 11 and under the socket 16 of platform 13.

Preferably, the upper surface of bottom wall 17 of socket 16 has a flat horizontal portion 24 directly over the joint, and the bottom wall 17 has a downwardly inclined portion 25 or guide project-

ing from the surface 24 toward and preferably extending slightly under the adjacent end of car 11, for a purpose to be hereinafter described.

The end of each car, having the platform 14 thereon, as represented by the end of car 11 in the drawing, is provided with improved auxiliary supporting means which preferably includes a load distributing member or lever bar 27 fulcrumed or pivoted intermediate its ends upon the sill members 12 of car 11 at points adjacent to the platform 14.

Preferably, the bar 27 is provided intermediate its ends with a bore 28 extending laterally therethrough, which bore is preferably enlarged or tapered gradually from its center laterally outward to each end of the bore. A shaft 29 passes through the bore 28, and the bar 27 is journaled thereon, being normally journaled thereon at the center laterally of the bar, that is, at the smallest diameter of the bore.

Various forms of draft means may be provided for permitting longitudinal movement of the cars relative to each other. In the form shown in the drawing, the ends of the shaft 29 extend through laterally opposite longitudinally extending slots 30 in the sill members 12 for permitting longitudinal movement of the shaft 29 in the sill members.

Preferably, the outer ends of the shaft 29 have square collars 31 secured thereon for abutting the outer surfaces of the sills 12. Means for yielding- 30ly resisting longitudinal movement of the shaft in the sills 12 in either direction may include springs 32 interposed between the collars 31 and the platform 14, and springs 33 interposed between the collars 31 and angle members 34 secured to each sill member at the opposite side of the shaft 29. The springs may have centering means such as the pins 35 and 36 secured to and extending in longitudinally opposite directions from the collars 31, and received respectively in apertures 37 in the platform 14, and in suitable apertures in the adjacent spring abutting angle members 34.

The end portion 40 of bar 27 extends under a raised portion 41 of platform 14 and is adapted to enter the socket 16 in platform 13. A roller 42 is journaled in the underside of end portion 40 for rolling upon the upper surface of the bottom wall 17 of the socket, and a roller 43 is yieldingly mounted on the end of the bar by means of springs indicated at 44, for abutting the inner surface of end wall 19 of the socket. The other end portion 46 of bar 27 extends under car 11 and toward the far end thereof, and is preferably downwardly inclined from the shaft 29.

The end of portion 46 may be provided with a yoke 47 adapted to fit around the squared portion 48 of axle housing 49 of a two wheel truck indicated generally at 50 and having wheels 51 rolling upon the rails R and carried by the axle 51a. Thus the bar 27, being movable on its pivot, forms a movable mounting or connection for car 11 on the auxiliary truck 50, and distributes the load of the end of car 11 between the main support and the auxiliary support when the cars are in coupled position.

Preferably, spring means indicated at 52 is interposed between the squared portion 48 of the axle housing and the upper wall of the yoke 47 for yieldingly resisting upward movement of the axle housing in the yoke 47, and the squared portion 48 is provided with studs 53 which are slideable in slots 54 in the yoke for permitting said movement.

Preferably, the bottom ends of the yoke are 75

detachably connected together under the axle housing as by bolts 56.

When the cars 10 and 11 are in coupled position as shown in Figs. 1 and 2, the roller 42 rests upon the flat portion 24 of socket 16 of car 10, immediately over the joint between said car and the main supporting truck 22. The weight of the adjacent end of car 11 is distributed through the shaft 29 and the lever arms 40 and 46 of the load distributing member 27, between the main supporting truck 22 and the auxiliary truck 50. The proportion of the load of car 11 which is carried by the auxiliary truck 50 depends entirely upon the lengths of the lever arms, or in other words upon the relative distances between shaft 29 and roller 42 and between shaft 29 and axle 51 of auxiliary truck 50. As shown in Figs. 1 and 2 the distance between the shaft 29 and the auxiliary truck axle is substantially twice that of the distance between the shaft 29 and roller 42, so that substantially one-third of the load of the end of car 11 is carried by the auxiliary truck and two-thirds by the main truck.

Obviously, the proportion of the load carried by the auxiliary truck may be varied to suit conditions by changing the location of the fulcrum of the lever bar 27 relative to its ends.

By always supporting a part of the load of car 11 upon the auxiliary truck, the wheels thereof will always rollably engage the rails R so as to insure good tracking thereof regardless of curvature and irregularities in the rails, thereby insuring an unvarying distribution of the load, and greater safety and efficiency in operation than where an auxiliary truck is arranged to "idle" on the rails, that is, to rollably engage the same without supporting any load.

Various forms of coupling means may be provided for maintaining the cars in the connected position shown in Figs. 1 and 2. I have shown a preferred form including a lever 60 pivotally connected to the platform 13 at one side of the socket 16 as at 61 and arranged to drop behind the upwardly projecting lug 62 on the end portion 40 of the bar 27 for holding the bar 27 and hence the car 11 in coupled position with car 10.

Preferably, a strengthening or back-up bar 63 is secured to platform 13 at the side of lever 60 toward car 11. The back-up bar 63 has a raised portion 64 at its central portion for permitting the lug 62 to pass thereunder during coupling and uncoupling of the cars.

At the opposite side of the socket from the pivot 61 the back-up bar 63 is provided with an upwardly extending arm 65 having an angular flange 66 at its upper end.

A spring 67 is preferably interposed between the flange 66 and the lever 60 for urging the lever 60 toward the coupled position behind the lug 62 as shown in Figs. 1 and 2. Preferably, a spring pressed latch 68 is connected to the handle 69 of lever 60 and adapted to enter notches in the upright arm 65 for holding the lever 60 in position to engage behind lug 62 or in raised position to permit uncoupling of the cars, and the latch is adapted to be held in released position by means of a ring 69a on handle 69.

Preferably, a supporting plate or bolster 70 is secured upon and extends laterally of the underside of car 11 for supporting the same upon the auxiliary truck when said car is uncoupled. The upper wall of yoke 47 may have a ball 71 rollably mounted thereon for bearing upon the concave undersurface 72 of the bolster 70 when the cars are uncoupled. The surface 72 is concaved

laterally so as to always tend to maintain the ball 71 at the center of car 11 and yet permit swinging of the car 11 upon the auxiliary truck. The bolster is provided with a downwardly projecting lug 74 at each side of concaved surface 72 for limiting the relative lateral movement of the car.

When it is desired to uncouple the car 11 from car 10, the coupling lever 60 is first manually raised against spring 67 to the dot-dash line position in Fig. 4, to permit the cars to be moved apart longitudinally. As the cars are moved apart the roller 42 will roll down the inclined portion or guide 25, and when the dot-dash position of Fig. 2 is reached the ball 71 will abut the bolster 70 to transfer all of the load of the adjacent end of car 11 onto the auxiliary truck 50 before the roller leaves the inclined projection 25.

When the cars are moved together for automatic coupling, the roller 42 strikes the downwardly inclined portion 25 of platform 13 in the manner shown in the dot-dash position of Fig. 2, and then as the cars move further toward each other the bar 27 acts as a lever to raise the adjacent end of car 11 until the upwardly projecting lug 62 on bar 27 passes under raised portion 64 of back-up bar 63 and the forward inclined surface of lug 62 wedgably engages the lever 60 to raise the same against the spring 67, the latch 68 having been previously released, after which the lever 60, urged by spring 67, will drop behind the projection 62 to prevent uncoupling of the cars. The shock of the impact between car 11 and car 10 is taken by the springs 44 when the roller 43 strikes the end wall 49, and the springs 44 act to hold the lug 62 in abutment with lever 60 when the cars are in coupled position.

As best shown in Fig. 1 the sides of the lever bar 27 are tapered inwardly from the bore 28 toward both ends of the bar to permit lateral swinging of the car 11 relative to the bar as the car travels around curves, the taper of the bore 28 being adapted to allow such movement.

Likewise, the sides of the end portion 40 of the bar 27 are preferably convexly rounded both longitudinally and vertically, and the inner surfaces of side walls 18 of socket 16 are also rounded longitudinally and vertically, so as to permit lateral swinging of or rocking of car 10 relative to bar 27 and always maintain point contact between the sides of the socket and the bar. Preferably, the roller 42 has its rolling surface rounded laterally for permitting easy rocking of the car 10 relative to the bar.

The improved car supporting means provides for improved riding qualities when the cars are coupled due to the fact that the cars are supported at their ends providing greatly increased length of wheel base, and yet provides for readily and easily coupling and uncoupling the cars at any time and at substantially any location.

Also, the cars may be made capable of longitudinal movement relative to each other when coupled, so that if desired the improved supporting means provides for starting a maximum number of cars in a train for a given motive power.

Moreover, the improved car supporting means provides for greatly reduced weight in a train of cars over the conventional way of having two full size trucks for supporting each car.

In case of derailment, the improved car supporting means tends to prevent the cars of a train from getting out of alignment, and therefore provides for increased safety.

The improved car supporting means provides for constructing a train having the advantages of the articulated type, with the additional advantages of being able to quickly and easily uncouple and automatically couple the cars by moving them toward or away from each other.

I claim:

1. In combination with a car adapted at one end to be detachably joined to another vehicle having main supporting means at said joint, an auxiliary support for said car, said auxiliary support being adapted to support said car end in uncoupled position, and means movably mounting said car on said auxiliary support for distributing the load of said car end between the main supporting means and the auxiliary support when the cars are in coupled position.
2. In combination with a car adapted at one end to be detachably joined to another vehicle having main supporting means at said joint, an auxiliary support for said car, said auxiliary support being adapted to support said car end in uncoupled position, and a load distributing member movably mounting said car on said auxiliary support for distributing the load of said car between the main supporting means and the auxiliary support when the cars are in coupled position.
3. In combination with a car adapted at one end to be detachably joined to another vehicle having main supporting means at said joint, an auxiliary support for said car, said auxiliary support being adapted to support said car end in uncoupled position, and a load distributing member movably mounting said car on said auxiliary support for distributing the load of said car between the main supporting means and the auxiliary support when the cars are in coupled position, and for transmitting all of the load of said car to the auxiliary support when the cars are in uncoupled position.
4. In combination with a car adapted at one end to be detachably joined to another vehicle having main supporting means at said joint, an auxiliary support on said car, said auxiliary support being adapted to support said car end in uncoupled position, and a load distributing member pivoted on the car and having one end connected to the auxiliary support and the other end carried by the main supporting means in coupled position for distributing the load of said car between the main supporting means and the auxiliary support.
5. In combination with a car adapted at one end to be detachably joined to another vehicle having main supporting means at said joint, an auxiliary support on said car, said auxiliary support being adapted to support said car end in uncoupled position, and a load distributing member pivoted on the car and having one end connected to the auxiliary support and the other end carried by the main supporting means in coupled position for distributing the load of said car between the main supporting means and the auxiliary support, the end of said load distributing member connected to the auxiliary support forming a connection between said support and said car in uncoupled position.
6. In combination with a car adapted at one end to be detachably joined to another vehicle having main supporting means at said joint, an auxiliary support on said car, said auxiliary support being adapted to support said car end in

uncoupled position, a load distributing member pivoted on the car and having one end connected to the auxiliary support and the other end carried by the main supporting means in coupled position for distributing the load of said car between the main supporting means and the auxiliary support, and a guide on the main supporting means for being movably engaged by the free end of the load distributing member as the car is moved toward or away from the vehicle for transferring part of the load of the car to or from the main supporting means.

7. In combination with a car adapted at one end to be detachably joined to another vehicle having main supporting means at said joint, an auxiliary support on said car, said auxiliary support being adapted to support said car end in uncoupled position, a load distributing member pivoted on the car and having one end connected to the auxiliary support and the other end carried by the main supporting means in coupled position, for distributing the load of said car between the main supporting means and the auxiliary support, a guide on the main supporting means for being movably engaged by the free end of the load distributing member as the car is moved toward or away from the vehicle for transferring part of the load of the car to or from the main supporting means, and means for locking the free end of the load distributing member to the vehicle when the free end of the load distributing member is carried by the main supporting means.

8. In combination with a car adapted at one end to be joined to another vehicle having main supporting means at said joint, an auxiliary support for said car adjacent the end thereof to be joined to said vehicle, a load distributing member having a portion forming a supporting connection between the auxiliary support and said car in uncoupled position, said load distributing member being arranged to distribute the load of said car between the main supporting means and the auxiliary support when the car is in coupled position, and means for holding the car and vehicle in coupled position.

9. In combination with a car adapted at one end to be joined to another vehicle having main supporting means at said joint, an auxiliary support for said car adjacent the end thereof to be joined to said vehicle, a load distributing member having a portion forming a supporting connection between the auxiliary support and said car in uncoupled position, said load distributing member being arranged to distribute the load of said car between the main supporting means and the auxiliary support when the car is in coupled position, means for holding the car and vehicle in coupled position, and means permitting slight longitudinal movement of the car relative to the vehicle in coupled position.

10. In combination with a car adapted at one end to be detachably joined to another vehicle having main supporting means at the joint, an auxiliary support on said car adapted to support said car end in uncoupled position, a load distributing member having a longitudinally slideable pivotal connection with said car, and means limiting the longitudinal movement of said car relative to said member, said member having one end connected to said auxiliary support and the other end carried by the main supporting means in coupled position.

EDWARD J. SATTLER.
